UNITED STATES PATENT OFFICE.

ALBERT H. HEBERT, OF HOLYOKE, MASSACHUSETTS.

ACETYLENE-GAS GENERATOR.

No. 841,148.

Specification of Letters Patent.

Patented Jan. 15, 1907.

Application filed June 24, 1905. Serial No. 266,780.

To all whom it may concern:

Be it known that I, ALBERT H. HEBERT, a citizen of the United States of America, residing at Holyoke, in the county of Hampden 5 and Commonwealth of Massachusetts, have invented a new and useful Acetylene-Gas Generator, of which the following is a specification.

My invention relates to improvements in 10 acetylene-gas generators in which a water-reservoir is mounted on a generator or gas-chamber with a cooling-chamber between; and it consists of these members, together with a peculiar carbid-holder in said gas-chamber, 15 a water-feed apparatus in said cooling-chamber, a condenser in said reservoir, and other subsidiary or auxiliary parts, all as herein-after set forth.

The objects of my invention are, first, to 20 produce a comparatively low and compact generator which is light for the amount of carbid it is designed to carry and which can be readily charged and cleaned and is easily controlled; second, to produce a generator 25 which is capable of supplying either one or a plurality of burners with equal facility, the single light alone being as steady as when burning with another or others, and vice versa; third, to furnish an apparatus in which the 30 generating process is quickly started and can be quickly stopped; fourth, to employ a comparatively small volume of water by utilizing the cooling-chamber and a central pipe for the purpose of obtaining the necessary head; 35 fifth, to afford adequate means for cooling both water and gas, and, sixth, to provide a practicable and efficient generator especially adapted for use on automobiles, which embodies all desired features of advantage, 40 including, among others, safety with genuine utility in its broadest sense.

I attain the objects and advantages above pointed out and others which will appear hereinafter by the means illustrated in the 45 accompanying drawings, in which—

Figure 1 is a front elevation of my generator; Fig. 2, a vertical section on lines $x-x$ looking in the direction of the arrow, Fig. 3; Fig. 3, a vertical section on lines $y-y$ looking 50 in the direction of the arrow, Fig. 2; Fig. 4, an enlarged section through the two-way valve; Fig. 5, a plan view of the carbid-holder, and Fig. 6 an end detail of a portion of said holder.

Similar letters of reference refer to similar parts throughout the several views.

My construction includes a generator-casing or gas-chamber A below and a casing B above, divided into a cooling-chamber a and a water-chamber b , the latter being in the 60 top of said casing B. A substantial bottom B', which forms the floor of the chamber a , is provided for the casing B, and this bottom or floor has laterally-extending bifurcated ears c. A groove a' is made in the under side of 65 the floor B', adjacent the edges thereof, to receive the upper edges of the casing A, and there is a packing c' of "live" rubber or equivalent material in said groove, so that a tight joint can be formed between the two casings. 70 On each side of the casing A is a forked lug d, having pivoted thereto at d' a rod d'', screw-threaded at its free terminal to receive a thumb-nut d'''. The two rods d'' are directly below the ears c when the casing B is in place 75 on the casing A. To securely fasten the casing B to the casing A, turn the rods d'' upward and into engagement with the ears c, the thumb-nuts d''' being above said ears. Then screw down said thumb-nuts tight onto 80 the ears. This operation produces an absolutely tight joint between the two casings. When it is desired to separate the casings, simply loosen the thumb-nuts d''' and disengage them and the rods d'' from the ears c. 85

I prefer to employ in this generator a vibrating or swinging carbid-holder, and in this connection attention is called to the holder C in the drawings, which is suspended at the ends on pins e e, projecting inward 90 from opposite sides of the chamber A. Each pin e is received into a vertical slot e' in the corresponding end of the holder, said slot extending from the point of suspension just below the upper edge downward through the 95 bottom edge, by which arrangement said holder can be easily and quickly removed and replaced in the gas-chamber and when in place therein is adapted to swing on the supporting-pins within the limits fixed by the 100 front and back of said chamber. The floor of the holder C is perforated, preferably consisting of wire mesh, to permit the residue or ashes from the disintegrating carbid to drop through into the space provided below 105 in the gas-chamber, and such floor is downwardly convex, by preference, so that the carbid will gravitate toward the center.

The slots e' in the ends of the carbid-holder are covered by inwardly-extending vertical 110 shields e'' e'', which leave plenty of space for the pins e and prevent the carbid from enter-

ing said slots. On the inside faces of the shields e'' are vertical ways or guides $e'''e'''$ for a plate or separator C' , the end edges of said separator operating in said guides. 5 Ears $e''''e''''$ at the upper corners of the separator C' bear on the upper edges of the guides e''' and limit the downward movement of said separator. While the top of the separator is about even with the top of the holder 10 C , the bottom of said separator is some distance above the bottom of said holder. The office of the separator is to prevent too much movement to the larger pieces of carbid in the upper part of the holder, while permitting 15 the fine carbid below to commingle freely as said holder vibrates and the ashes to be shaken out. The separator is made removable to enable it to be taken out while the holder is being cleaned and to facilitate 20 cleaning the separator itself and more particularly the drip-receiver f . The drip-receiver f is a vertical pipe located in the center of the separator and extending below the same nearly to the floor of the holder. The 25 receiver is closed at the bottom, but has perforations f' in the sides adjacent such bottom.

In order to get to the inside of the chamber A for the purpose of removing the ashes and 30 refilling the carbid-holder after the generator has been used and the supply of carbid exhausted it is necessary to take off the casing B , with its contents. After recharging the casing is returned to place and secured, and it 35 is with this last condition in view that the following description of parts and of operation is given. Before proceeding with this description, however, it should be clearly understood that the lower terminal of the drip- 40 receiver f is buried in the carbid below the horizontal plane of the lower edge of the separator C' and that the finer portions of the carbid inevitably work to the bottom of the mass, where a thorough commingling is 45 brought about by the vibratory motion imparted to the holder C from the motion of the machine, the carbid above said plane being kept more or less steady by said separator, but eventually passing downward to be 50 broken up and disintegrated like that which has preceded.

The reservoir b has a filling-hole b' in the top, closed by a screw-cap b'' vented at b''' . g is a strainer below the hole b' .

55 Within the cooling-chamber a are two vertical pipes h , opening at the top into the reservoir b , two horizontal pipes h' , connected at their outer ends by elbows with said pipes h and at their inner ends with a T h'' , a horizontal pipe i , opening at the back into said T and at the front through a constricted curved terminal into a vertical receptacle i' , a small pipe i'' extending upward from the T forward and downward to the top of said receptacle, and a valve-casing j , having a two-

way valve j' therein at the base of the receptacle. A small drip-pipe k depends from the casing j , passes through the floor B' , and enters the open upper end of the receiver f . A vertical gas-pipe l , open at the bottom and closed at the top, extends from the top of the chamber A through the chamber a into the upper part of the reservoir b . A vertical gas and waste pipe m is also located partly in the cooling-chamber and partly in the reservoir, such pipe being closed at both ends. Within the cooling-chamber an inclined waste-pipe m' extends between the lower terminal of the pipe m and the valve-casing, and a second waste-pipe m'' passes from the opposite side of said valve-casing out through one of the openings a'' in the casing B , emptying at the outer end. In each of the pipes h is a filling n of wicking or other suitable absorbent material, and there is a similar filling n' in the pipe i , only the latter filling is about one-half as dense as each of the others. In Fig. 3 the pipe i is partially broken away to expose the filling therein.

The valve j' has two through-passages o and o' therein, the former being arranged to connect the passage in the drip-pipe k with that in the receptacle i' when the valve is properly positioned and the latter to connect the passages in the waste-pipes m' and m'' when the position of the valve is right for this purpose. A stem j'' extends forward from the valve j' through the front side of the chamber a , and fast upon the protruding terminal is a pointer j''' , also a suitable handle. Three indicator marks and characters for the same appear on the face of the front of the casing B convenient to the pointer j''' , such characters reading as follows from left to right: "1 0 2." The arrangement of parts is such that when the pointer j''' is at "1" the water-feed is open and the waste-passage closed, when at "2" the water-feed is closed and the waste-passage open, and when at "0" both are closed.

In addition to the large openings $a'' a''$ in the end walls of the chamber a there are holes a''' in the front and rear walls thereof. Thus provision is made for a free circulation of air in and out of said chamber and throughout the same, to the end that the water in the reservoir above is kept cool, as are the several members and their contents in the chamber itself. This compartment may be styled an "air-chamber" as well as a "cooling-chamber."

Within the reservoir b is an inclined pipe p , attached at its higher end to the gas-pipe l , and at its lower end to the gas and waste pipe m . I prefer to employ here a coil of pipe; so as to obtain more surface exposure to the water or cool air in the reservoir, since such pipe serves as a condenser, as will presently appear. The pipe m is provided near the top with one, two, or more outlets for

gas, a connection or connections being made between such outlet or outlets and the burner or burners.

5 *q* represents an outlet or outlet-tube extending from the pipe *m* out through the adjacent walls of the reservoir *b* and casing *B*.

To start the generator, assuming that all is in readiness, open the water-feed by turning the pointer *j'''* to "1," when water from the 10 reservoir enters the receiver *f* through the valve and the drip-pipe *k*, the valve-passage *o* now standing vertically. Also open one or more burners, as the case may be. The proper feed is insured by the presence of the 15 filling in the pipes *h'* and *i* and the constructed entrance to and exit from the receptacle *i'*. The water drips into the receiver *f* at the top and escapes through the perforations *f'* at the bottom to unite with the carbid and 20 assist in generating gas. The gas thus generated rises through the pipe *l*, circulates through the pipe or coil *p*, where it yields whatever moisture may be contained therein, or at least a considerable proportion of such 25 moisture, and finally passes through the pipe *m* and the outlet *q* (or outlets) and connection (or connections) to the burner, (or burners,) where it is ignited. No connection or 30 burner is shown. The water in the coil *p* finds its way into the pipes *m* and *m'*, but cannot escape by way of the pipe *m''* until the valve is turned to bring its passage *o'* into a substantially horizontal position, as when the pointer *j'''* is at "2."

35 When the amount of gas generated becomes excessive from any cause, the increased pressure is immediately relieved by the entrance of gas into the drip-pipe *k* and the consequent shutting off of the water-supply to 40 the carbid. The gas forces the water out of the pipe *k* and the receptacle *i'* through the pipe *i'''* into the **T** *h''* and out of said **T** and the pipes *h'* and *h* back into the reservoir without disturbing to any extent the water 45 contained in the filling *n'* in the pipe *i*. What-

ever gas may find its way into the reservoir can escape through the vent *b'''* in the screw-cap *b''*. As soon as the surplus moisture around the base of the receiver *f* has been 50 used up the gas-pressure becomes normal again, and the water commences once more to drip from the receptacle *i'*, the wet condition in which the filling *n'* was left at the time the gas drove the water from the adjacent pipes causing a prompt resumption of 55 the water-feed operation.

Since there is a double quantity of filling in each of the pipes *h'* to that in the pipe *i*, the seepage of water through the latter is practically equal to that through both of said pipes *h'* together; hence the steady and even supply or feed under ordinary circumstances.

60 The generator will continue to work as long as there is any carbid remaining in the holder unless the water-feed be sooner shut

off, and then enough moistened carbid remains to generate some little gas and supply the light or lights a while longer; but if it is desired to take advantage of this the pointer *j'''* should be turned from "1" to 70 "0" instead of to "2," so as to close the feed-passage without opening the waste-passage; otherwise the gas either wholly or in part would be liable to escape through the latter passage instead of passing to the igniting 75 point or points.

At any time during generation the generator can be closed down by turning the pointer to "2." Then the water ceases to drip into the receiver, and the accumulation of water 80 in the pipes *m* and *m'* escapes through the valve and the pipe *m''*. Gas also can escape this way in the event that the burner or burners has or have been closed before exhausting the generator, the gas then assisting to clear 85 out the waste-passage. Were the pointer turned to "0" instead of to "2" in closing down the generator, the water-feed would be cut off, to be sure; but no way would be left open for the waste water and gas, if any, to 90 pass off. The water-feed and waste passages should not ordinarily be both closed at once except in the case mentioned in the preceding paragraph.

Although the receiver *f* swings with the 95 holder and separator, the water-feed is not affected thereby, because said receiver is enough larger than the pipe *k* to permit of the necessary motion.

It will be obvious to one skilled in the art 100 that various changes may be made in this generator and its parts without departing from the nature of my invention, and I desire to include and cover all such changes which fall within the scope of my invention. 105 In this connection I wish to state that one set of pipes *h* and *h'* may be omitted and fairly good results obtained under some conditions with the remaining set of corresponding pipes. 110

What I claim as my invention, and desire to secure by Letters Patent, is—

1. The combination, in an acetylene-gas generator, of a generator-casing proper having a gas-chamber therein, a separate independent casing of like area arranged to rest upon and be secured to the first-mentioned casing, said supplementary casing having a water-reservoir in the upper portion and a cooling-chamber in the lower portion thereof, the end walls of said cooling-chamber being cut away to give free access to the interior thereof, and the side walls of said cooling-chamber being substantially continuous excepting for air-passage openings therein, water-feed conduits from said reservoir and a two-way-valve casing and valve in the cooling-chamber, said water-feed conduits communicating with the generator-chamber, a gas-pipe passing through the cooling-cham- 125 130

ber from said gas-chamber to the reservoir, and waste-pipe connections in the cooling-chamber, said valve controlling both the water-feed and the waste, substantially as and 5 for the purpose set forth.

2. The combination, in an acetylene-gas generator, with a casing provided with supporting means projecting inward from opposite walls thereof, of a carbid-holder having 10 recesses to receive said supporting means and adapted to be supported thereby and to swing in said casing while extending substantially the entire distance between two of its walls.

15 3. The combination, in an acetylene-gas generator, with a gas-chamber, of a vibrating carbid-holder therein, and a separator in said holder, the bottom of said separator being above the bottom of the holder.

20 4. The combination, in an acetylene-gas generator, with a gas-chamber provided with interior pins, of a carbid-holder slotted to receive such pins and adapted to be suspended therefrom.

25 5. The combination, in an acetylene-gas generator, with a gas-chamber provided with interior pins, of a carbid-holder slotted to receive such pins and adapted to be suspended therefrom, and shields in said holder for the 30 slots.

35 6. The combination, in an acetylene-gas generator, with a gas-chamber provided with interior pins, of a carbid-holder slotted to receive such pins and adapted to be suspended therefrom, shields in said holder for the slots, provided with guides, and a separator adapted to be held in place by such guides.

40 7. The combination, in an acetylene-gas generator, with a gas-chamber, of a carbid-holder therein, a separator in said holder, the bottom of said separator being above the bottom of the holder, and a drip-receiver in the holder extending below and opening below the horizontal plane of the bottom of the 45 receiver.

50 8. The combination, in an acetylene-gas generator, with a water-feed apparatus consisting in part of a drip-pipe, of a vibrating carbid-holder, and a drip-receiver supported in said holder in operative relation with said drip-pipe.

55 9. The combination, in an acetylene-gas generator, of a gas-chamber, a water-reservoir, water-feed apparatus leading from said reservoir to said gas-chamber, a valve-casing and a valve forming part of such apparatus, a condenser-coil in the reservoir, a gas connection between the gas-chamber and said coil, a waste-water connection between the 60 coil and said valve-casing, said valve controlling both the water-feed and the waste, and a gas-outlet from that part of the waste-water connection which is in the reservoir.

65 10. The combination, in an acetylene-gas generator, with a gas-chamber, and a water-

reservoir, of connecting feed apparatus comprising pipes leading from said reservoir to a common connection, a pipe leading from such connection, a receptacle connected with the last-mentioned pipe, and a drip-pipe 70 leading from said receptacle into said gas-chamber.

11. The combination, in an acetylene-gas generator, with a gas-chamber, and a water-reservoir, of connecting feed apparatus comprising pipes leading from said reservoir to a common connection, a pipe leading from such connection, a receptacle connected with the last-mentioned pipe, a drip-pipe leading from said receptacle into said gas-chamber, and a 80 valve interposed between the receptacle and drip-pipe.

12. The combination, in an acetylene-gas generator, with a gas-chamber, and a water-reservoir, of connecting feed apparatus comprising pipes leading from said reservoir to a common connection, a pipe leading from such connection, a receptacle connected with the last-mentioned pipe, a second pipe leading from said connection to said receptacle, 90 and a drip-pipe leading from the latter into said gas-chamber.

13. The combination, in an acetylene-gas generator, with a gas-chamber, and a water-reservoir, of connecting feed apparatus comprising pipes leading from said reservoir to a common connection, absorbent filling in such pipes, a pipe leading from such connection, absorbent filling in this pipe, a receptacle connected with the last-mentioned pipe, and a drip-pipe leading from said receptacle into 95 said gas-chamber.

14. The combination, in an acetylene-gas generator, with a gas-chamber, and a water-reservoir, of connecting feed apparatus comprising pipes leading from said reservoir to a common connection, absorbent filling in such pipes, a pipe leading from such connection, absorbent filling in this pipe of less density than that in the other pipes, a receptacle connected with the pipe which leads from the connection, and a drip-pipe leading from said receptacle into said gas-chamber.

15. Feed apparatus, for an acetylene-gas generator, comprising the water-reservoir, a water-receptacle having a drip-pipe connected therewith, and supply-pipes leading from said receptacle and adapted to be connected with said reservoir, the connection between the receptacle and said supply-pipes being 115 smaller than either.

16. Feed apparatus, for an acetylene-gas generator, comprising a water-reservoir, a water-receptacle, and pipes, having absorbent filling in certain of them, leading from said 125 receptacle and adapted to be connected with said reservoir, the connection between the receptacle and said pipes being smaller than either.

17. Feed apparatus, for an acetylene-gas 130

generator, comprising a water-reservoir, a water-receptacle, pipes leading from said receptacle and adapted to be connected with the reservoir, and absorbent filling of different densities in certain of said pipes, the denser filling being nearer the reservoir.

18. Feed apparatus, for an acetylene-gas generator, comprising a water-reservoir, a water-receptacle, supply-pipes leading from said receptacle and adapted to be connected with said reservoir, and a by-passage pipe connecting said receptacle with said supply-pipes at a point between the receptacle and reservoir connections.

19. The combination, in an acetylene-gas generator, with a gas-chamber, a water-reservoir, and an open-air or cooling chamber between said gas-chamber and reservoir, of supply-pipes arranged in angular relation with each other in said cooling-chamber and opening into said reservoir, a water-receptacle connected with said supply-pipes at the end opposite that which opens into the reservoir, a drip-pipe connected with said receptacle, and a valve adapted to control the flow of water from the receptacle into said drip-pipe.

20. The combination, in an acetylene-gas generator, of a gas-chamber, a water-reservoir, an open-air or cooling chamber between said gas-chamber and reservoir, supply-pipes arranged in angular relation with each other in said cooling-chamber and opening into the reservoir, a water-receptacle connected with said supply-pipes at the end opposite that which opens into the reservoir, a drip-pipe connected with said receptacle, a condenser in the reservoir, a connection between the gas-chamber and one end of said condenser, a combined gas and waste pipe connected with the other end of the condenser, a gas outlet pipe or pipes leading from the upper

part of said last-mentioned pipe and a waste-conduit leading from the lower part thereof, and a valve arranged and adapted to control both the flow of water from the receptacle into said drip-pipe and the escape of water or gas or both through said conduit.

21. The combination, in an acetylene-gas generator, with a gas-chamber, a water-reservoir, and an open-air or cooling chamber between said gas-chamber and reservoir, of supply-pipes arranged in angular relation with each other in said cooling-chamber and opening into the reservoir, a water-receptacle connected with said supply-pipes at the end opposite that which opens into the reservoir, absorbent filling in the horizontal portions of the supply-pipes, a drip-pipe connected with said receptacle, and a valve adapted to control the flow of water from the receptacle into said drip-pipe.

22. The combination, in an acetylene-gas generator, with a gas-chamber, a water-reservoir, and an open-air or cooling chamber between said gas-chamber and reservoir, of supply-pipes arranged in angular relation with each other in said cooling-chamber and opening into the reservoir, a water-receptacle connected with said supply-pipes at the end opposite that which opens into the reservoir, absorbent filling of different densities in the horizontal portions of the supply-pipes, a drip-pipe connected with said receptacle, and a valve adapted to control the flow of water from the receptacle into said drip-pipe.

In testimony whereof I have signed my name to this specification in the presence of two subscribing witnesses.

ALBERT H. HEBERT.
